UNITED STATES PATENT OFFICE.

FRANK E. FORD, OF CHICAGO, ILLINOIS, ASSIGNOR TO THE EXCELSIOR STEEL FURNACE COMPANY, OF CHICAGO, ILLINOIS, A CORPORATION OF ILLINOIS.

FURNACE-CASING BONNET.

Application filed August 3, 1928. Serial No. 297,176.

My present invention relates to improvements in knock-down furnace casing bonnets with integral top and completely fabricated side walls.

5 I am aware that furnace casings, as well as bonnets, have heretofore been made in sections to be assembled at the place the furnace is erected, but in designing a structure of this kind it is desirable to complete the structure 10 so far as possible in the factory, both in order to reduce the amount of assembly necessary on the job and because the factory work is capable of much better systemization and checking, which conserve economy and secure 15 a more sturdy and dependable structure.

As will be hereafter seen, my improved casing bonnet, when it leaves the factory, comprises two parts only—a top and the side wall, which may be readily assembled with 20 each other and the usual top casing ring and when so assembled will have the same sturdiness and dependability as a casing bonnet which was made and completely assembled in final form in the factory.

25 The one piece or integral top and the completely fabricated side wall of my casing bonnet are not only stronger but are also more resistent to rust than similar elements joined or articulated from any larger number of parts, and are also more nearly air tight.

It will also be hereafter seen and noted 30 that the assembly hereinafter shown between the top and side walls of the bonnet materially reinforces and strengthens both of these elements as well as the completely assembled structure.

I have attained the foregoing objects and 35 accomplished the aforementioned results by 40 means of the structure illustrated in the accompanying drawing, in which—

Fig. 1 is an elevation partly in section of 45 one form of a furnace casing bonnet embodying my invention.

Fig. 2 is an elevation partly in section of a modified form of a furnace casing bonnet embodying my invention.

Fig. 3 is a fragmental sectional detail showing the manner of assembly of side and top wall in the form shown in Fig. 1.

50 Fig. 4 is a section on line 4—4 of Fig. 2 showing the juncture between the ends of the side wall.

Similar reference characters refer to similar parts throughout the several views. 55

In both forms of structure herein illustrated it is preferred to make the top of the bonnet a single integral piece of metal as being better adapted to withstand the atmospheric moisture and the changes of temperature to which the structure is subject in service. The side wall of both forms also should be made of as few pieces as possible, although the vertical or nearly vertical disposition of the side of the bonnet serves to 60 protect them to a considerable extent from both receiving and retaining moisture or other foreign matter deposited thereon by condensation or gravitation from the surrounding atmosphere. 65

In the form of structure shown in Fig. 1 the one piece top wall 8 is given an inverted pyramidal form. The edges or periphery of the top 8, which is circular, are bent over and under a flange 9 extending laterally from a 70 circumferential annulus or ring 10, in the center of which is a bead 11. The flange 9 is further secured within the turned edges of the top 8 by crimping these parts, as at 12, after the flange 9 has been inserted in the 75 hook or loop of the edge of the top. This assembly is clearly shown in Fig. 3.

In the form of structure shown in Fig. 1 the side wall 13 inclines inwardly from the bottom to the top and around the top of the side wall 85 is provided a bead 14 to engage with the bead 11 of the ring 10. The bottom of the side wall of the structure shown in Fig. 1 is also crimped, as at 15, and given a vertical disposition so as to fit against the vertical flange 90 16 of the ordinary form of furnace casing ring, which, as is well known, is provided with an exterior shoulder 17 running around the middle thereof against which the ends of the upper and lower casing segments abut. 95 As shown in Fig. 4 one end of the side wall is provided with a transverse shoulder 18 between the bead 14 and the crimping at 15. The end is carried beyond the shoulder 18, as at 19, and then bent back upon itself, as at 20, 100 and then backwardly again parallel to the part 19, as at 21, to form a slot or pocket 22 for the reception of the other end of the side wall.

Secured to the opposite ends of side wall 105 13 are pairs of right angle or L-shaped brack-

ets 23, one leg of these brackets being riveted or otherwise secured to the wall 13 opposite each other. The outstanding arm of the L-shaped brackets 23 are bored to receive the 5 bolt or machine screw 24, on the end of which screws the nut 25.

In assembling my bonnet the side wall is unrolled and is disposed about the ring 10 with its upper end abutting the flange 9 and 10 the bolt 24 is placed in the upper pair of brackets, so as to hold these pieces loosely 15 in assembly. The bottom of the side wall is then fitted to the casing ring 16 and a bolt 24 in the bottom pair of brackets 23 is inserted 20 and turned up. By adjusting the two bolts a great degree of rigidity between the elements can be secured and the crimping of the lower end of the side wall where it assembles with the casing ring permits the adaption of 25 these members to one another with great nicety.

The structure shown in Fig. 2 differs only from that shown in Fig. 1 in having a flat top 8^a instead of an inverted pyramidal top, 25 and in having vertical side wall 13^a instead of slightly inclined side wall.

By stacking the tops and rolling the sides one within another space can be conserved both in shipment and storage and in assembly 30 the ring 10 with its flange 9 materially reinforces and strengthens both the top and side wall and the completed structure when these parts are assembled.

Having described my invention what I 35 claim as new and desire to secure by Letters Patent is:

1. A bonnet for a furnace casing comprising a one piece top of circular form, the edges whereof are turned over to engage the lateral 40 flange of a laterally flanged and centrally beaded annulus or ring, and a side wall one longitudinal edge whereof is beaded to engage the bead in said annulus or ring, and the other longitudinal edge whereof is crimped, 45 a transverse pocket on one end of said side wall adapted to receive the other transverse

end thereof, and means for drawing and securing the entering edge into the pocket of the opposing edge.

2. A bonnet for furnace casing comprising 50 a top of circular form, the edges whereof are turned over to engage and are crimped upon the lateral flange of a laterally flanged and centrally beaded annulus or ring, and a side wall, one longitudinal edge whereof is beaded 55 to engage the bead in said annulus or ring, and the other longitudinal edge whereof is crimped, a transverse pocket on one end of said wall adapted to receive the other transverse end thereof, and means for drawing 60 and securing the entering edge into the pocket of the opposing edge.

3. A bonnet for a furnace casing comprising a one piece top of circular form, the edges 65 whereof are turned over to engage the lateral flange of a laterally flanged and centrally beaded annulus or ring, and a side wall, one longitudinal edge whereof is beaded to engage 70 the bead in said annulus or ring, and the other longitudinal edge whereof is crimped, and means for securing the transverse ends of 75 said side wall together.

4. A bonnet for a furnace casing comprising a one piece top of circular form, the edges 80 whereof are turned over to engage the lateral flange of a laterally flanged annulus or ring, and a side wall, one longitudinal edge whereof engages 85 said annulus or ring, and the other longitudinal edge whereof is crimped, and means for securing the transverse ends of said side wall together.

5. A bonnet for a furnace casing comprising a one piece top of circular form, the edges whereof are turned over to engage the lateral flange of a laterally flanged and centrally beaded annulus or ring, and a side wall, one longitudinal edge whereof is beaded to engage 90 the bead in said annulus or ring, and means for securing the transverse ends of said side wall together.

FRANK E. FORD.
